PRINTING MECHANISM

Arthur M. Youngs, Trenton, N. J., assignor to
 Youngs Rubber Corp. of N. J., Trenton, N. J., a
 corporation of New Jersey

Application July 16, 1940, Serial No. 345,848

7 Claims. (Cl. 101—40)

This invention relates to new and useful improvements in printing mechanisms and particularly to mechanisms for successively printing a series of continuously passing articles. More specifically the invention is concerned with mechanism for printing prophylactic articles of thin rubber and is a continuation-in-part of co-pending application Serial No. 265,018, filed March 30, 1939.

The principal object of the invention is to provide a novel mechanism for legibly and distinctly printing matter upon a series of continuously moving articles of manufacture.

Another object of the invention is to provide a mechanism for printing various legends, trademarks or other matter on thin rubber prophylactic articles.

Still another object of the invention is to provide a printing mechanism of the type described wherein the article being printed is accurately controlled during printing thereof.

A further object of the invention is the provision of means whereby the thin rubber article is expanded to a desired diameter before coming in contact with the printing plate, thereby insuring a clean cut impression when the article assumes its normal diameter.

A still further object of the invention is to provide a mechanism of the character described having means for preventing the articles from engaging said mechanism when it is desired not to print them.

These and other objects and features of the invention and the various features and details of its construction and operation are hereinafter fully set forth and shown in the accompanying drawings, in which:

Figure 1 is a semi-diagrammatic view in perspective of an article testing apparatus having associated therewith the printing mechanism of the present invention;

Figure 2 is a side sectional elevation of the printing mechanism taken on line 2—2, Figure 1;

Figure 3 is a view in front elevation of the mechanism shown in Figure 2;

Figure 4 is a view in section taken on line 4—4, Figure 2; and

Figure 5 is a view in section taken on line 5—5, Figure 2.

Referring now to the drawings, Figure 1 illustrates one form of apparatus in conjunction with which may be employed the printing mechanism of the present invention. This particular apparatus is more particularly shown and described in the copending application hereinabove re-

ferred to and reference numeral 1 designates, generally, an endless conveyor of the articulate link type comprising a series of pairs of links 2 pivotally connected by pins 3 interposed between said links for engagement with the teeth of sprocket wheels 4 and 5 on which said conveyor is carried. Movement of the conveyor is continuous in the direction of the arrows and driving power is applied to the sprocket 5 from a motor 6 as shown. A series of bars 7 are, secured transversely at intervals along the conveyor and pivotally connected to opposite ends of each of these cross bars 7 by means of spindle 8 for swinging movement in a plane perpendicular to the plane of travel of said conveyor is a mandrel or like support designated generally at 9 adapted to receive thereon thin rubber prophylactic articles.

These mandrels 9 comprise a body portion 10 of suitable material such as metal and a base or hub portion 11 of hard rubber, micarta, Bakelite or the like. The shape of the main body portion 10 of the mandrel conforms substantially to that of the rubber article to be printed upon but is of greater diameter and length than the normal diameter and length of the said rubber articles so that the latter are supported thereon in a relatively stretched condition. These mandrels are described at length in co-pending application Serial No. 320,633, filed February 24, 1940. As shown in Figure 2, the hub portion 11 of the mandrel is a relatively thick sleeve and is journaled upon the pivotally mounted spindle 8 by means of suitable ball bearing structure so as to permit rotation of the mandrels freely about said spindles. Thus the mandrels 9 including their body 10 and base portions 11 are free to rotate about the spindles 8 and at the same time by virtue of the pivotal connection of said spindles with the conveyor 1 are movable in a plane perpendicular to the plane of travel of the latter. The mandrels 9 are supported in the desired angular position laterally of the conveyor 1 by means of tracks or guides 12 disposed at either side thereof and in contact with the hub portion 11 of said mandrels, so that the latter roll therealong and rotate about their spindles 8 as they are advanced by the said conveyor 1.

Now in operation and use of the apparatus shown in Figure 1 of the drawings, the thin rubber articles are placed upon the mandrels 9 at the designated loading station, after which they travel in the direction of the arrows about the sprocket wheel 5, and then pass through a liquid test bath B. From the test bath travel of the articles continues in the same direction about the

sprocket 4 and then through a printing mechanism P, after which they arrive at the designated station where they are inspected and removed from the mandrels.

It is the printing mechanism P referred to above that forms the subject matter of the present invention, and the construction and operation of the same will now be described. As shown, there is provided a printing mechanism at both or opposite sides of the conveyor as shown in Figure 1, but as these mechanisms are identical in construction and operation, a description of one of them is all that is necessary, and from this point on the description of the invention, its construction and operation will deal, for the most part, with only one of these mechanisms, except where necessity requires otherwise.

Accordingly, and referring to Figure 3 of the drawings, it will be seen that the previously mentioned mandrel tracks 12 are omitted or interrupted at the printing station, and that during passage through the printing mechanism, the mandrels 9 are supported by a leather covered auxiliary track portion 13 which is vertically adjustable as desired by means of screws or the like 14 carried by brackets 15 secured to and extending laterally from angle rails 16 which underlie and support the conveyor 1 through its cross bars 7 during the greater extent of the lower course of travel of said conveyor. In order to prevent wobbling of the conveyor and mandrels during passage thereof through the printing mechanism, the cross bars 7 of the conveyor 1 are held firmly upon the rails 16 by members 17 which are suspended from the main frame structure 18 and vertically adjustable in order that their pressure upon said bars 7 may be regulated.

Mounted transversely of the apparatus is a printing mechanism drive shaft 20. This shaft 20 is journaled in bearings 21 and has secured thereon a sprocket wheel 22 which is rotatably driven by the conveyor 1 through engagement of the pins 3 thereof with the teeth of said wheel 22. Also secured on the drive shaft 20 is a smaller sprocket wheel 23, and through a chain 24 this sprocket 23 drives another sprocket wheel 25 secured on a shaft 26 which is rotatably journaled above and parallel to the said drive shaft 20.

Secured on this shaft 26 is a pulley 27 for driving a belt 28 which is passed about said pulley 27 and also two idler pulleys 29 rotatably mounted upon stud shafts 30 and positioned so that the belt 28 thereon engages downwardly upon the base portions 11 of the mandrels 9 so as to rotate the latter during their passage through the printing mechanism upon the leather covered track portion 13. As best shown in Figure 2 of the drawings, this track portion 13 has recessed portions 31 therein to provide sufficient clearance for the mandrels to pass beneath the belt 28 at the pulleys 29, thus enabling the provision of a reduced clearance between said belt 28 and track section 20 at the printing point so that sufficient pressure will be exerted by the belt upon the mandrel to urge it into engagement with the printing roll or platen 32 with enough force to insure a good print upon the thin rubber article carried by said mandrel.

The printing roll or platen 32 is secured upon a drive shaft 33 rotatably journaled in bearings 34 and 35. This printing roll or platen 32 is polygonal in shape, thus providing a series of flat peripheral surfaces upon each of which is secured a printing pad 36. The printing roll shaft 33 has secured thereon a ratchet 37, and

this is periodically actuated to rotate the said shaft 33 in a counterclockwise direction (reference being had to Figure 3) by means of a pawl 38 which is pivotally carried by a collar 39 journaled on the shaft 33 and operated by a link 40 driven from an eccentric crank 41 secured on a shaft 42. The other or inner end of this shaft 42 carries a gear 43, and this gear 43 meshes with a gear 44 on the main driving shaft 20.

The shaft 42 is thus driven from the main shaft 20 in timed relation therewith, and hence in timed relation with the travel of the conveyor 1 and the ratios of the various driving connections between the conveyor 1, the main shaft 20 and the shaft 42 are such that the pawl 38 actuates the ratchet 37 and the shaft 33 so that the printing pads 36 on the hexagonal faces of the printing roll 32 are successively brought into upwardly facing printing position as each succeeding mandrel 9 with its article passes the printing point.

A roll 45 for applying ink to the several printing pads 36 is disposed adjacent the printing roll 32 and mounted upon a shaft 46 which is driven through gears 47 and 48 from the printing roll shaft 33, the inking roll 45 being urged into contact with the printing pads 36 by means of a spring 49. In addition to the inking roll 45, there is provided an ink applying and distributing roll 50 carried by an arm 51 pivotally mounted on a shaft 52 and connected together at their extremities by a pin from which extends an adjustably mounted arm 53 for supporting a weight 54 that may be moved therealong to regulate the pressure of the roll 50 against the inking roll 45. Ink may be applied to the roll 50 either manually or from a fountain or like supply as desired.

When it is desired not to print any matter upon the articles carried by the mandrels 9, the latter may be caused to pass through the printing mechanism without contacting the printing roll 32, for example, by providing a bracket 55 having thereon a traction surface 56, and arranging the said bracket so that it can be elevated, thus causing the surface 56 to engage the hub portion 11 of said mandrels 9, thus likewise raising the latter. This bracket 55 is biased downwardly upon a wedge-shaped lever 57 by a spring 58, and hence elevation of said bracket and the mandrels 9 may be effected by manually moving said wedge-shaped lever 57 further beneath the bracket 55.

From the foregoing description, it will be observed that the present invention provides a novel mechanism for applying printing upon a continuously moving succession of articles and, in the particular adaptation of the invention illustrated, as the mandrel-supported rubber prophylactic articles pass through the printing station, there is timely presented for rolling contact by each succeeding article one of a series of inked printing pads which move successively into printing position in timed relation with the travel of the said articles.

The invention is not limited in its application and use to the particular apparatus and articles disclosed, but may be employed generally for printing any moving succession or series of articles, and while a particular embodiment of such a printing mechanism has been herein illustrated and described, it is not intended that the invention be limited to such disclosure, but that changes and modifications may be embodied and

incorporated therein within the scope of the annexed claims.

I claim:

1. In article handling apparatus comprising conveyor means for advancing a series of articles and means for driving said conveyor in one direction along a predetermined path of travel, a shaft mounted for rotation with its axis perpendicular to the path of travel of the conveyor, a printing member fixed on said shaft adjacent said conveyor and having a series of printing surfaces thereon for engagement by the articles advanced by the conveyor, a ratchet secured on the shaft, a collar rotatable on said shaft, a pawl pivotally carried by said collar and arranged in cooperative relation to said ratchet, a drive shaft driven from said conveyor drive means, a stud shaft, means for driving said stud shaft from the drive shaft in predetermined timed relation with respect to the latter and the travel of the conveyor, an eccentric crank carried by said stud shaft, and a link connecting said eccentric crank and the collar operable to actuate the latter and the pawl thereby periodically to actuate the ratchet and its shaft to present the printing surfaces on the printing member successively to the articles advanced by said conveyor.

2. In article handling apparatus comprising conveyor means for advancing a series of articles and means for driving said conveyor in one direction along a predetermined path of travel, a shaft mounted for rotation with its axis perpendicular to the path of travel of the conveyor, a printing member fixed on said shaft adjacent said conveyor and having a series of printing surfaces thereon for engagement by the articles advanced by the conveyor, a ratchet secured on the shaft, a collar rotatable on said shaft, a pawl pivotally carried by said collar and arranged in cooperative relation to said ratchet, a drive shaft driven from said conveyor drive means, a stud shaft, means for driving said stud shaft from the drive shaft in predetermined timed relation with respect to the latter and the travel of the conveyor, and means driven by said stud shaft operable to actuate the pawl thereby periodically to actuate the ratchet and its shaft to present the printing surfaces on the printing member successively to the articles advanced by said conveyor.

3. In article handling apparatus comprising conveyor means for advancing a series of article supporting elements and means for driving said conveyor in one direction along a predetermined path of travel, a track section for supporting said elements during at least a portion of their travel, a shaft mounted for rotation with its axis perpendicular to said track section, a printing member fixed on said shaft adjacent the track section and having a series of printing surfaces thereon for engagement by the articles traversing said track section, a ratchet secured on the shaft, a collar rotatable on said shaft, a pawl pivotally carried by said collar, a drive shaft driven from said conveyor drive means, a stud shaft, means for driving said stud shaft from the drive shaft in predetermined timed relation with respect to the latter and the travel of the conveyor, an eccentric crank carried by said stud shaft, and a link connecting said eccentric crank and the collar operable to actuate the latter and the pawl thereby periodically to actuate the ratchet and its shaft to present the printing surfaces on the printing member successively to the articles traversing the track section.

4. In article handling apparatus comprising

conveyor means for advancing a series of article supporting elements and means for driving said conveyor in one direction along a predetermined path of travel, a track section for supporting said elements during at least a portion of their travel, a shaft mounted for rotation with its axis perpendicular to said track section, a printing member fixed on said shaft adjacent the track section and having a series of printing surfaces thereon for engagement by the articles traversing said track section, a ratchet secured on the shaft, a collar rotatable on said shaft, a pawl pivotally carried by said collar, a drive shaft driven from said conveyor drive means, a stud shaft, means for driving said stud shaft from the drive shaft in predetermined timed relation with respect to the latter and the travel of the conveyor, and means driven by said stud shaft operable to actuate the pawl thereby periodically to actuate the ratchet and its shaft to present the printing surfaces on the printing member successively to the articles traversing the track section.

5. In article handling apparatus comprising conveyor means for advancing a series of rotatably mounted article supporting elements and means for driving said conveyor in one direction along a predetermined path of travel, a track section for supporting said elements during at least a portion of their travel, a shaft mounted for rotation with its axis perpendicular to said track section, a printing member fixed on said shaft adjacent the track section and having a series of printing surfaces thereon for engagement by the articles traversing said track section, a ratchet secured on the shaft, a collar rotatable on said shaft, a pawl pivotally carried by said collar, a drive shaft driven from said conveyor drive means, a stud shaft, means for driving said stud shaft from the drive shaft in predetermined timed relation with respect to the latter and the travel of the conveyor, an eccentric crank carried by said stud shaft, a link connecting said eccentric crank and the collar operable to actuate the latter and the pawl thereby periodically to actuate the ratchet and its shaft to present the printing surfaces on the printing member successively to the articles traversing the track section, another shaft driven from said drive shaft, a pulley rotatable with said other shaft, and a belt driven by said pulley and operable to engage and effect positive rotation of the article supporting elements during travel upon said track section adjacent said printing member.

6. In article handling apparatus comprising conveyor means for advancing a series of rotatably mounted article supporting elements and means for driving said conveyor in one direction along a predetermined path of travel, a track section for supporting said elements during at least a portion of their travel, a shaft mounted for rotation with its axis perpendicular to said track section, a printing member fixed on said shaft adjacent the track section and having a series of printing surfaces thereon for engagement by the articles traversing said track section, a ratchet secured on the shaft, a collar rotatable on said shaft, a pawl pivotally carried by said collar, a drive shaft driven from said conveyor drive means, a stud shaft, means for driving said stud shaft from the drive shaft in predetermined timed relation with respect to the latter and the travel of the conveyor, and means driven by said stud shaft operable to actuate the pawl thereby periodically to actuate the ratchet

and its shaft to present the printing surfaces on the printing member successively to the articles traversing the track section, another shaft driven from said drive shaft, a pulley rotatable with said other shaft, and a belt driven by said pulley and operable to engage and effect positive rotation of the article supporting elements during travel upon said track section adjacent said printing member.

7. In article handling apparatus comprising conveyor means for advancing a series of rotatably mounted article supporting elements and means for driving said conveyor in one direction along a predetermined path of travel, a track section for supporting said elements during at least a portion of their travel, said track having a recessed portion, a shaft mounted for rotation with its axis perpendicular to said track section, a printing member fixed on said shaft adjacent the recessed portion of the track section and having a series of printing surfaces thereon for engagement by the articles traversing said track

section, a ratchet secured on the shaft, a collar rotatable on said shaft, a pawl pivotally carried by said collar, a drive shaft driven from said conveyor drive means, a stud shaft, means for driving said stud shaft from the drive shaft in predetermined timed relation with respect to the latter and the travel of the conveyor, an eccentric crank carried by said stud shaft, a link connecting said eccentric crank and the collar operable to actuate the latter and the pawl thereby periodically to actuate the ratchet and its shaft to present the printing surfaces on the printing member successively to the articles traversing the recessed portion of the track section, another shaft driven from said drive shaft, a pulley rotatable with said other shaft, and a belt driven by said pulley and operable to engage and effect positive rotation of the article supporting elements during travel upon said track section adjacent said printing member.

ARTHUR M. YOUNGS.
